TWO-PIECE FOUR-IN-HAND NECKTIE

Mark H. McWhirter, McCamey, Tex., assignor
of one-half to Edwin G. Stafford, McCamey,
Tex.

Application July 10, 1934, Serial No. 734,536

1 Claim. (Cl. 2—155)

This invention relates to a two-piece four-in-hand necktie.

It is desirable to make a four-in-hand necktie of a simple and efficient construction, as well as very attractive in appearance. Therefore, an object of this invention is to produce a two-piece four-in-hand necktie that shows one beautiful or attractive design throughout, with no interruption or break, because of my novel built-in structure of all of the units going to make up my improved device.

It is well known that the repeated tying and untying of a knot in the ordinary four-in-hand necktie causes the scarf soon to become wrinkled and stringy, not only by the successive formation of the knot, but by the necessity of sliding the relatively narrow end of the scarf through the knot in the operation of causing the neck encircling portion of the necktie and the knot, to snugly encircle and engage the neck of the wearer, hence it is an object of this invention to produce a necktie which, when it has been tied by the individual wearer can be permitted to remain with the fixed knot, merely by unfastening the two pieces, when it is desired to remove the tie, or quickly fasten the two pieces together when the necktie is placed in position by the wearer.

Further, by my built-in structure, no unsightly parts are in evidence, the whole appearance of my improved article being as a single design of a beautiful and attractive configuration, pleasing to the eye, hence a ready seller.

In this beautiful necktie that I have produced, I also reinforce the parts, which increases the life of the tie, without presenting an interrupted design, or obvious spliced parts that may have been done in the construction of ties prior to this invention.

With the foregoing and other objects in view, my invention comprises certain novel constructions, combinations and arrangements of parts as will be hereinafter fully described, illustrated in the accompanying drawing, and more particularly pointed out in the appended claim.

45 In the drawing:

Figure 1 is a perspective view of the necktie adjusted and tied into a four-in-hand.

Figure 2 is a bottom plan view of the primary section, while

50 Figure 3 is a bottom plan view of the auxiliary section.

Figure 4 is a sectional view taken on line 4—4, Figure 3 and looking in the direction of the arrows.

55 Figure 5 is a greatly enlarged sectional view taken on line 5—5, Fig. 4.

Referring to the drawing by numerals, 1 designates the primary section and 2 the auxiliary section of my improved necktie. In actual practice these two sections appear as if they are more or less of a beautiful two-piece structure without any interruption or disfigurement, as with ordinary ties that are made up of distinctly separable or united parts. In the primary section 1 the design runs through the tab 3, at the inner end, which is stitched transversely at 4, making a very strong structure; this tab 3 is provided with preferably the male section 5 of the snap fastener, whereby the two sections are detachably secured together. The female section 6 of the snap fastener is attached to tab 1 which is stitched across at 8 to make a non-expansile tab, for carrying the female section 6. As seen in Fig. 4, the head 9 of the female section 6 is in a pocket formed in the tab 7. This pocket 9 is practically a continuation of pocket 10 (Fig. 4) which is formed in the auxiliary section for receiving the elastic strip 11. The pocket portion of the auxiliary section has its ends designated by "A" and "B", Fig. 3. This pocket portion 10 is puckered throughout its length between points "A" and "B". This puckering is hardly seen upon casually viewing the necktie, but it allows expansion of the section 2 between points "A" and "B" of about one-third or one-half of its normal length. Of course, the elastic piece built into the section is normally at rest or unexpanded; when unexpanded, then the part 12 of the necktie is puckered; when the rubber piece is expanded for the adjustment or fixing of the tie in place, then the puckered part is stretched to its normal condition or unpuckered. This puckered portion of the auxiliary section is longitudinally reinforced by a series of parallel lines of stitching 13, between points "A" and "B". This makes a very desirable structure, assisting in increasing the life of the necktie. The auxiliary section is provided with longitudinally-extending stitching 14, beyond point "B", as shown in Fig. 3.

In the enlarged section shown in Fig. 5, I have illustrated the puckered pocket portion of the auxiliary section 2 for better understanding the important structure thereof.

It is to be understood that while I have shown a snap fastener attaching the inner ends of the sections together, still other fastening means may be used on the unexpansile pads built into the primary and auxiliary sections.

The whole of the tie—the two sections—is of the same general appearance, or design, making

a very beautiful effect without any unsightly splicing or piecing since my novel built-in structure of the elements making up the tie are not apparent to the casual observer.

5 The user takes the two sections and fastens them together and then ties the desired knot, to suit his individual taste. Then by simply unfastening the contiguous ends, the necktie can be removed from the neck without disturbing 10 the knot. Some users prefer a tight knot and others a loose knot, hence my efficient invention permits the necktie to be adapted to the individual needs and taste. The puckered expansion pocket of the built-in construction herein 15 described greatly simplifies the fastening and unfastening of the sections by giving desired length of the parts for efficient and expeditious operation.

20 While I have described the preferred embodiment of my invention and illustrated the same in the accompanying drawing, certain minor changes or alterations may appear to one skilled in the art to which this invention relates during the

extensive manufacture of the same, and I, therefore, reserve the right to make such changes or alterations as shall fairly fall within the scope of the appended claim.

What I claim is:

As a new article of manufacture, a two-piece four-in-hand necktie, comprising a primary section provided with a tab on its inner end, an auxiliary section provided with a tab on its inner end, said auxiliary section provided at the inner end of said tab with a puckered built-in pocket portion, a flat elastic strip in said pocket portion, a series of parallel lines of stitching through said puckered pocket portion and flat elastic strip and extending longitudinally of the auxiliary section, said auxiliary section also provided with longitudinally extending reinforcing lines of stitching beyond the puckered pocket portion, and detachable fastening means on the contiguous faces of said tabs at the inner ends of said sections, substantially as shown and described. 10 15 20
